NO-PUNCH BINDER

Herbert L. Davis, Atlanta, Ga.

Application April 29, 1939, Serial No. 270,834

3 Claims. (Cl. 129—36)

The object of my invention is to provide a novel binder by which a series of loose leaves, sheets or pages may be bound together without the necessity of punching holes in the sheets, leaves or pages. I attain this and other objects of my invention by the device illustrated in the accompanying drawing, in which—

Figure 1 is a side elevation of the binder before any sheets have been inserted in it;

10 Fig. 2 is a plan view of same;

Fig. 3 is a side elevation of the binder in expanded form; and

15 Fig. 4 is a section on line 4—4 of Fig. 3, but showing sheets inserted between the binding strips 4 and 5.

Like characters of reference designate like parts in each of the several views.

Referring to the accompanying drawing, I provide a binder consisting of a plurality or series of binding strips such as strips 1, 2, 3, 4, and 5. The outer binding strip 1 is secured near its ends to the rods 6 and 7, and the other binding strips 2, 3, 4, and 5 are slidably mounted on said rods but the outer binding strip 5 is limited in its 25 range of movement by the heads 8 of rods 6.

I also provide a series of binder strip adjustment screws 1a, 2a, 3a, and 4a, which are attached to successive binder strips 1, 2, 3, and 4 by the screw heads 1b, 2b, 3b, and 4b, as shown 30 in Figs. 1 and 3.

Between each of the binder strips the desired sheets, leaves or pages P may be inserted, as shown in Fig. 4, and fastened tightly by adjusting binder strip screws 1a, or 2a, or 3a, or 4a, to 35 tighten the binder strips on the pages, according to which strips engage the pages P.

It will be noted that the heads 8 of the rod 6 limit the movement of the outer binder strip 5 on rods 6, as shown in Figs. 3 and 4.

40 The screw 1a has a threaded engagement with the binder strip 2; screw 2a has a threaded engagement with binder strip 3; screw 3a has a threaded engagement with binder strip 4; and the

screw 4a has threaded engagement with the binder strip 5, whereby the respective binder strips may be adjusted by operating the screws with which they have a threaded engagement. While screw 1a has a threaded engagement with binder strip 5, it is only loosely mounted in binder strips 3, 4, and 5; similarly, while screw 2a has a threaded engagement with binder strip 3, it is only loosely mounted in binder strips 4 and 5; and while screw 3a has threaded engagement with binder strip 4 it is only loosely mounted in binder strip 5. By reason of this arrangement separate adjustment of any of the binder strips relative to the strip next below it by operating the screw by which it has threaded engagement, is possible.

What I claim is:

1. A binder of the type described, having a series of binder strips to engage leaves, a series of adjusting screws, one of said screws being secured to each of the binder strips except the uppermost strip and having a threaded engagement with the next adjacent binder strip, and guide rods for the binder strips, and means for limiting the expansion of the binder strips.

2. A binder of the type described, having a series of binder strips to engage leaves, a series of adjusting screws, each of said screws being secured at one end to a binder strip and having a threaded engagement with the next adjacent binder strip, and end guide rods for the binder strips, said end guide rods having projecting heads limiting the expansion of the outer binding strip.

3. A binder of the type described, having a series of binder strips to engage leaves, a series of adjustable screws, each of said screws having one end secured to a binder strip, and having a threaded engagement with the next adjacent binder strip, end guide rods for the binder strips, and means for limiting the expansion of the binder strips.

HERBERT L. DAVIS.
